UNITED STATES PATENT OFFICE.

CHARLES PARKER BREESE, OF NORFOLK, VIRGINIA.

VALVE FOR INTERNAL-COMBUSTION ENGINES.

1,123,233.

Specification of Letters Patent.

Patented Jan. 5, 1915.

Application filed March 23, 1914. Serial No. 826,712.

To all whom it may concern:

Be it known that I, CHARLES PARKER BREESE, a citizen of the United States, and resident of Norfolk, in the county of Norfolk and State of Virginia, have invented certain new and useful Improvements in Valves for Internal-Combustion Engines, of which the following is a specification.

This invention relates to valves which have a sliding movement and which open and close ports by moving into registry with and then away from same, and particularly to that class of such valves which employ two sliding members with ports that register at times when a passageway is to be opened, but move out of registry in order that the valve ports may pass the fixed opening without establishing communication therewith, when the passageway should be closed.

One feature of the present invention consists in having the valve members in the form of concentric hollow bodies provided with a housing independent of but in communication with the engine cylinder and constructed to provide, by the space within them, passageways for the flow of the medium to be controlled, such as exhaust gases, or fuel constituents, or both; to which end, the valve so constructed is interposed between the engine cylinder and a passageway or passageways whose communication with the engine cylinder is to be periodically established and interrupted.

Another feature of the invention relates to means whereby an appreciable portion of the heat of exhaust gases may be conserved for the purpose of conditioning the incoming new charge of fuel; to which end, the invention contemplates a single valve structure for both the exhaust and intake passages, actuated so that it controls these passages successively and in a manner that will cause the walls of the valve structure to be heated by the exhaust gases and to impart heat to the incoming charge even though the valve chamber forming part of the exhaust passage may be separate and distinct from that forming part of the intake passage.

A further object is to provide effective means of economical construction for actuating the valve structure from a suitable shaft, to which end a further feature of the invention consists in employing a single actuating member, preferably in the nature of a link connection having a traveling movement for phasing valves and an oscillating

movement relatively to the valve members, for bringing their ports into and out of registry and, therefore, determining the opening and closing of the passageways through the valve structure; this operating means being preferably in the form of a link pitman having a cross head extending between the valve members in position to develop relative movement of said members as the cross head oscillates, and a stem extending rigidly from said cross head to a suitable crank whereby to develop both the traveling and oscillating movement of the link member thus provided.

Further objects relate to details of construction whereby the apparatus is economical to produce and convenient to keep in order as will appear more at length from the following detail description.

In the accompanying drawings—Figure 1 is a vertical axial section of a reciprocating engine and a valve embodying the several features of the present invention; the main shaft being assumed to rotate clockwise, and the valve shaft counter-clockwise; and the parts being in position assumed at commencement of exhaust. Figs. 2, 3 and 4 are detail views of the valve structure showing the parts in position of fuel intake, compression stroke, and working stroke, respectively. Fig. 5 is a section on the line 5^x—5^x of Fig. 1.

Referring to the drawings in detail, C represents the working cylinder, P the piston and S the crank shaft of an internal combustion engine, while E represents an exhaust passage, F a fuel supply passage and s a valve shaft which, for purposes of illustration, is shown as being driven with a two to one speed reduction, through the gear wheels s' and S'.

1 represents a single port in the cylinder C, which is used for both fuel intake and exhaust.

2 and 3 are a pair of concentric cylindrical valve members suitably housed to reciprocate in a valve chest 4 in communication with the port 1 of the main cylinder and with the exhaust passage E and fuel passage F. The inner valve member has upper and lower chambers e, f, adapted to constitute parts of the exhaust and supply passages, respectively, when the valve members are properly positioned. The member 2 is provided with a combined exhaust and supply port 2^a, and the member 3 with an exhaust

port 3^a, both of which ports are adapted to register simultaneously with the cylinder port 1 at suitable intervals, and said members 2 and 3 are also provided with exhaust ports 2^b and 3^b which register with exhaust passage E, whenever ports 2^a, 3^a meet at the port 1. The inner member 3 is further provided with an independent supply port 3^c which is adapted to combine with port 2^a to open the port 1 into the fuel chamber f at certain intervals and while the port 2^a still remains opposite port 1; and said members 2 and 3 are provided with supply ports 2^d and 3^d which are adapted to open communication to said chamber f from the fuel supply passage F, whenever ports 2^a, 3^c meet at the port 1. Furthermore, the members 2 and 3 are adapted to move relatively so that even when port 2^a is passing port 1, or port 2^b or 2^c is passing the fuel passage F, no communication will be established across the valve, as for instance during either the compression or the working stroke of the engine.

From the foregoing, it will be seen that the valve structure has a traveling movement to develop the different phases of valve action and relative movement between its respective members to determine when the valve shall be opened and closed. These movements are preferably imparted through a single member 5 which is in the form of a link connected to extensions 3^x, 2^x of the respective valve members at 5^a and 5^b and extending rigidly to the shaft s, which may be provided with a crank bend or any of the recognized mechanical equivalents thereof, such as an eccentric. One of the connections, for instance that shown at 5^b, provides lost motion in a transverse direction to compensate for changes in angular position of the link relatively to the valve members.

The operation of the valve structure is as follows: Assuming the engine shaft S to rotate clockwise and the valve shaft s to be rotated anti-clockwise, and with the piston P approaching its lower limit under expansion of the ignited charge, the valve members will bear the relation to each other shown in Fig. 1 and will begin to uncover the port 1 and establish its communication with the exhaust passage E, which relation will continue until piston P executes its upward scavenging stroke, when the crank shaft S will pass its upper limit and rock the link 5 from the position of Fig. 1 to the position of Fig. 2, and bring the intake port 3^c opposite the port 1 and port 3^d opposite the passage F, and establish free passage for fuel intake, as shown in Fig. 2. During this shifting of the inner valve member 3, the outer valve member 2 has remained approximately stationary, lowering effect incident to the rocking of the link being very slight in view of the distribution of forces incident to the travel of the crank s from

the position of Fig. 1 to the position of Fig. 2. The working piston now moves downward again to its lower limit. During this movement, the rocking of the link to the left from the position of Fig. 2 draws the outer member 2 downward to close the port 1, after which the valve members move downward together. By the time the compression stroke is well under way, the valve parts are in the position shown in Fig. 3, with both passages cut off. By the time the compression stroke is completed and the working stroke is under way, the crank s has again rocked to the right and the valve members shifted relatively to the position shown in Fig. 4, after which the crank s begins to move the valve members upward until at completion of the working stroke, when the piston P is again in the position of Fig. 1, ports 2^a, 3^a on one side, and ports 2^b, 3^b on the other side will be in registry and the exhaust position will begin to develop as already explained.

The particular method of operating the valve members is desirable, because permitting the valves to be readily withdrawn by merely disconnecting from the crank s and removing the cap 4^a of the housing 4. Both the cranks S and s are located in the same crank chamber, and the parts may thus be subjected to the same splash lubrication.

As indicated in Fig. 5, the horizontal dimensions of the several ports and passages may be relatively large and this in turn provides for ample capacity without undue vertical dimensions, and consequently admits of reduction in the vertical travel of the valve members. By the close relationship of the exhaust and supply passages and the integral character of their walls, heat from the exhaust will be appreciably distributed to the incoming fuel and will assist in conditioning the latter.

I claim:

1. An engine valve comprising overlapping members having traveling movement and movement relatively to each other; said members being interposed between the ports to be connected and being constructed with ports brought into registry with each other by their relative movement and into communication with the ports to be connected by their traveling movement, and a single driving connection for said valve members having a traveling movement for deflecting the traveling movement of the valve members, and an oscillating movement for developing relative movement between said valve members.

2. An engine valve comprising overlapping members having traveling movement and movement relatively to each other; said members being interposed between the ports to be connected and being constructed with ports brought into registry with each other

- by their relative movement and into communication with the ports to be connected by their traveling movement, and a single driving connection for said valve members having a traveling movement for deflecting the traveling movement of the valve members, and an oscillating movement for developing relative movement between said valve members; said driving connection comprising a link member connected with the respective valve members at points offset laterally from the direction of its traveling movement.
3. In an engine valve, the combination of a pair of overlapping members adapted to move longitudinally and relatively to each other, a link member for actuating said valve members and a shaft having connection with said link member, which develops both traveling and oscillating movement
- 5
- 10
- 15
